UNITED STATES PATENT OFFICE.

RICHARD GREENLEAF TURNER, OF WORCESTER, MASSACHUSETTS, ASSIGNOR TO THE CROMPTON & KNOWLES LOOM WORKS, OF WORCESTER, MASSACHUSETTS, A CORPORATION OF MASSACHUSETTS.

FEELER MOVABLE TO DISTRIBUTE WEAR ON YARN.

Application filed November 2, 1925. Serial No. 66,156.

This invention relates to weft detecting mechanism for looms and it is the general object of the invention to provide means for giving the detecting surface a traversing motion with respect to the yarn to be detected to the end that any wearing incident to the blows struck by the detector may be distributed over a yarn area larger than the area of the yarn engaging portions of the detector.

When so-called rayon is used as warp in the weaving of fabrics its elastic limit is found to be so low that the stretching normally incident to opening the shed gives it a permanent set and for this reason rayon has not generally been satisfactory as warp up to the present time. It is necessary, therefore, to introduce this yarn as filling but it is so fine that a single bobbin will remain in the shuttle long enough to cause undesirable abrasion at the point where the weft detector strikes the yarn. Attempts have been made to avoid this abrasion by using very light springs to resist the forward movement of the detector when engaging the yarn, but this results in less certainty of operation. It has also been proposed to use intermittently operative feelers normally held out of operative position but moved at periodic intervals into detecting position.

When the latter method is applied to a box loom it is found necessary to release the detector so that the same will strike the yarn every time a box changes and when a pattern calls for frequent alternations between rayon and yarn of another character or color the advantage of the intermittent detector is largely lost. It is a further object of my invention to prevent the abrasion alluded to by moving the detector longitudinally with respect to the bobbin so that on each detecting beat a slightly different surface of yarn is struck by the detector.

It is a still further object of my invention to combine a regularly oscillating member of the usual multi-color weft replenishing mechanism with a traversing motion for the detector.

It is a further object of my invention to provide the weft replenishing, controlling, and actuating members in relatively fixed

positions but so related to the detector that they can be controlled by the latter when in any of its different positions.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a top plan view of my improved detecting mechanism showing the same positioned to detect the yarn near the butt of the bobbin, parts being shown in section,

Fig. 2 is a front elevation of the mechanism shown in Fig. 1, with certain parts in section,

Fig. 3 is a vertical longitudinal section through the detector at right angles to the bobbin and showing the detector in the position it assumes when first engaged by a full bobbin as the latter advances.

Fig. 4 is a detail elevation of the right hand end of Fig. 2 but showing the parts in a different position, and

Fig. 5 is a vertical section on line 5—5 of Fig. 2.

Referring to the drawings it will be seen that I have provided a loom frame 10 on which is mounted a detector stand 11 having an upstanding arm 12 in which is mounted for free vertical motion a head 13. Said head receives a down motion on the detecting beat and an up motion on the non-detecting beat of the loom by mechanism not shown. A floating actuating lever 14 is pivoted as at 15 to the head 13 and has one end thereof connected by rod 16 to a lever 17 freely movable about a shaft 18 journaled in the weft detecting mechanism frame 19. Said arm 17 has a finger 20 spaced from and overhanging a portion of said lever 17 to define an open slot which receives a color slide 21. Said slide is mounted on arms 22 one of which is shown in Fig. 1 secured to the rock shaft 18.

The other end of floating lever 14 extends into a slot 23 formed in a second arm 24 upstanding from the stand 11. Said arm 24 is provided with an opening 25 transverse

2 to the slot 23 and proportioned to receive a controller pin 26 which as shown herein is normally out of the path of the floating lever 14. When said controller pin is under the lever 14, head 13 will descend to give a left hand oscillation to the shaft 18. A pin 27 passes through the upper portion of arm 24 and extends across the slot 23 in position to engage the upper surface of the adjacent end of lever 14 to cause said floating lever to move to the dotted line position shown in Fig. 2 when the head 13 is raised. It is to be understood that this latter movement occurs every second pick when the shuttle is on the opposite side of the loom and results in giving a periodic right hand oscillation to shaft 18. The traverse motion to be described hereinafter is derived from this periodic right hand motion of shaft 18 and for a further description of the mechanism thus far described reference may be had to Patent No. 1,030,748.

10 The weft detector comprises a bed 30 having a slot in the upper face thereof over the opposite longitudinal edges of which extend caps or guide plates 31 held to the bed in any manner. A detector slide 32 moves in the slot and is restrained from upward accidental displacement by the caps. Depending 20 from said slide is a clip 33 through which extends a rod 34 having a threaded head 35 to extend through the rear end of the bed 30. A compression spring 36 lies between the bed and the clip and serves to hold the slide 32 yieldingly in rear position as shown in Figs. 1 and 3.

15 A pin 37 secured in opposite walls of the slide 33 has pivotally mounted thereon the lower rear end of an indicator lever 38 slotted as at 39 to receive the forward end of a pin or yarn penetrating detector 40 as shown in Fig. 3. The slide 32 has secured thereto a broad blunt yarn impinging detector 41 as seen in Figs. 1 and 3 and the pin 45 detector member 40 extends through said yarn impinging detector and extends rearwardly to enter the yarn as shown in Fig. 1. A compression spring 42 lying between the slide and the indicating lever holds the latter normally in the full line raised position shown in Fig. 2.

20 A transmitting lever 43 is pivoted as at 44 to a fixed part of the stand 11 and is connected at the left end as shown in Fig. 1 to the controller pin 26 and has the other end thereof extended as shown in Figs. 2 and 3 to be normally below the indicating lever 38. A spring 45 lying between the arm 24 and a collar 46 secured to the controller pin 26 holds the lever 43 yieldingly against an adjusting screw 47.

25 So long as sufficient yarn for continued weaving is present the penetrating detector 40 will enter the yarn as the bobbin moves forwardly and no relative motion of the

detectors will take place so that the indicator lever 38 moves forwardly without engaging the transmitting lever 43. When insufficient yarn for continued weaving is present the pin detector 40 will not be able to enter the 70 yarn and the same will be pushed forwardly to depress the indicator lever to the dotted line position shown in Fig. 3 before the 75 yarn impinging detector 41 is acted upon to move forwardly. As the bobbin continues to advance the indicating lever will be moved into engagement with the transmitting lever 43 to rock the same and cause the controller pin 26 to move under actuating lever 14 at the time that head 13 descends. The type of weft detecting mechanism described herein is of well known construction and forms no particular part of my invention. It is to be understood that other forms of detectors can be associated 80 with the bed 30 and I do not wish to be limited to the particular detector illustrated herein.

85 As previously stated my invention relates to mechanism for giving the yarn engaging 90 surfaces of the detector a traverse motion and in carrying out the invention I provide the stand 11 with a slot 60 extending substantially parallel to the bobbin. A tongue 61 integral with and depending from 95 the bed 30 extends into slot 60. Said stand 11 is provided with a slot 62 communicating with slot 60 and through which extends a stud 63 secured in the tongue 61. Said stud 63 has a washer 64 and a head 65 which 100 prevents upward displacement of the bed 30 with respect to the stand 11.

105 In order to provide the traverse motion, I provide a guide rod 66 which moves freely through arm 24 and is threaded into one 110 side of the bed 30 as at 67. A comparatively light spring 68 is interposed between the arm 24 and the bed and tends to move the latter to the right as shown in Figs. 1 and 2. I extend a pair of arms 69 from the 115 right hand end of stand 11 and secure therein a stub shaft 70 on which is mounted for free rotation a traversing element T comprising a heart cam 71 secured to a ratchet wheel 72 having teeth 73 lying between relatively deep flanges 74. A boss 75 extending from the bed 30 substantially in alignment with the guide rod 66 has adjustably secured therein a cam engaging shoe 76.

120 To drive the traversing element T a rod 77 is connected as at 78 to an arm 79 rotating with shaft 18 to receive a downward motion on every alternate pick when the shuttle is on the opposite side of the loom. The lower end of the rod 77 has a rod head 80 adjustably secured thereto and provided with a tooth 81 adapted for engagement with the teeth 73. Said head 80 is held by gravity in operative engagement with the ratchet 125 and is restrained against lateral movement 130

by flanges 74. A relatively heavy compression spring 82 lies between one of the arms 69 and the traversing element to cause friction between said element and the other arm 69 so that pressure of the shoe 76 against the cam 71 will not cause rotation of the traversing element.

The operation of the device will be understood by referring to Fig. 2 where it will be seen that the detector and its bed have been moved to the extreme left position by the high point of the heart cam 71. As shaft 18 continues to receive its oscillating movements to the right the tooth 81 will give the ratchet a step by step movement and the comparatively light spring 68 will hold shoe 76 against the cam to permit a gradual motion of the bed to the right until the parts assume the position indicated in dotted lines in Fig. 1 and in full lines in Fig. 4. Continued rotation of the ratchet and heart cam will start the detector bed in the reverse direction and it will ultimately move back to the position shown in Fig. 2. This traversing of the bed 30 carries the detector along the bobbin to engage a larger area of yarn than the area of the yarn engaging part of the detector, thus distributing the blows and reducing the abrasions of the yarn.

The right end of transmitting lever 43 is extended to be in engageable position with the indicating lever 38 in any lateral position of the detector, and the latter is effective to give an indication of exhaustion of weft in any position.

From the foregoing it will be seen that I have provided means for giving the detecting surfaces a traverse motion so that the blows which the yarn receives from the detectors will be distributed over a relatively large area of yarn. Any device for giving rotary movement to the traversing element T may be employed other than that set forth herein and as previously stated other forms of detector may be mounted on the bed 30. Also, the controlling and actuating elements are in relatively fixed positions but are at all times under the control of the detector irrespective of the position of the latter.

Having thus described my invention it will be apparent that changes and modifications may be made therein by those skilled in the art without departing from the spirit and scope of the invention and I do not wish to be limited to the details herein disclosed but what I claim is:

1. In a loom having a supply of weft, a detector to cooperate with the same, and means to give said detector a regular progressive movement in the direction of the length of the weft to present the same to different portions of the weft independently of the position of the weft relatively to the loom.

2. In a loom having a supply of weft, a detector to cooperate with the weft to determine the condition of the same, and regularly acting means independent of the relative position of the weft with respect to the loom, to give said detector a different position along the length of the weft supply on successive detecting beats of the loom.

3. In a loom having a supply of weft, a weft detector to cooperate with the supply of weft to determine the condition of the same, and regularly acting means independent of the relative position of the weft with respect to the loom to give said detector a traversing motion with respect to the weft to present said detector to different portions of the weft on successive detecting beats of the loom.

4. In a loom having a supply of weft, a detector to cooperate with the supply of weft, and regularly acting means independent of the relative position of the weft with respect to the loom to cause a step by step relative movement between the weft supply and the detector to present a different surface of weft to the detector on successive detecting beats of the loom.

5. In a loom having a surface to be detected, a weft detector, a member receiving a regular motion independently of the detector each detecting beat of the loom, and connections between the member and the detector to move the latter to different positions along the surface to be detected to cooperate with the latter at a plurality of different points.

6. In a loom having a supply of weft, a weft detector, a carriage to support said detector, and regularly acting means independent of the relative position of the weft with respect to the loom to give said carriage a regular motion substantially parallel to the length of the weft supply to be detected to present the detector to a plurality of different surfaces on the weft supply.

7. In a loom having a weft supply, a weft detector to cooperate therewith, a carriage, a support for the carriage, and regularly acting means independent of the relative position of the weft with respect to the loom to give said carriage a progressive movement along the support to present the detector to a plurality of different surfaces on the supply of weft.

8. In a loom having a weft supply, a detector cooperating with the same, a movable support for the detector, a regularly moving cam, and connections between the cam and the support to move the latter and the detector in a direction substantially parallel to the length of the surface to be detected.

9. In a loom having a weft supply, a detector to cooperate with and ascertain the condition of said weft supply, a support for said detector movable in a direction sub-

stantially parallel to the length of the weft supply, a cam, a regularly oscillating member, connections between the regularly oscillating member and the cam to move the latter, and connections between the cam and the support to move the latter to give the detector a new position on each detecting beat of the loom.

10. In a loom having a weft supply, a regularly oscillating lever, means operable by said lever when the same moves in one direction to give the detector a movement along the length of the weft supply, controller mechanism, and connections between the detector and controller mechanism rendered operative at substantial exhaustion of weft by the motion of the regularly moving lever in the opposite direction.

11. In a loom having a weft surface to be detected, a weft detector, a mounting for said detector to keep the latter always in the same vertical position, and regularly acting means independent of the relative position of the weft with respect to the loom to give 25 said detector a progressive movement rela-

tively to the surface to be detected to present different weft surfaces to the detector.

12. In a loom having a weft carrier with a surface to be detected, a weft detector, means acting independently of the carrier to move said detector along the surface to be detected so that different portions of the surface to be detected will be presented to the detector on successive detecting beats of the loom, and means to effect indication of weft exhaustion when the detector is in any of its positions.

13. In a loom having a weft carrier with a surface to be detected, a weft detector, means acting independently of the carrier to move said detector progressively so that the same will engage a different portion of the surface to be detected on successive beats of the loom, and means to effect indication of weft exhaustion when the detector is in any of its progressive positions.

In testimony whereof I have hereunto affixed my signature.

RICHARD GREENLEAF TURNER.
